United States Patent Office

Des. 193,885
Patented Oct. 16, 1962

193,885

FAUCET

Roy Andrews, Mansfield, Ohio, assignor to Borg-Warner Corporation, Chicago, Ill., a corporation of Illinois

Filed Mar. 14, 1962, Ser. No. 69,253

Term of patent 14 years

(Cl. D91—3)

FIG. 1 is a perspective view of the faucet embodying my new design;

FIG. 2 is a top plan view thereof with the spout broken away in part for convenience of illustration;

FIG. 3 is a side elevation with the spout fragmentarily shown for convenience of illustration;

FIG. 4 is a front elevation thereof with the lever arm fragmentarily shown for convenience of illustration and with the spout shown in section along line 4—4 of FIG. 2.

I claim:

The ornamental design for a faucet, substantially as shown and described.
